GAS ADMINISTERING

Elmer I. McKesson, Toledo, Ohio; Martha F. McKesson, executrix of said Elmer I. McKesson, deceased, assignor to Martha F. McKesson, Toledo, Ohio

Application March 10, 1930, Serial No. 434,587

1 Claim. (Cl. 128—203)

This invention relates to gas administering.

This invention has utility when incorporated in apparatus for checking the condition of a patient and administering gas to the patient, more particularly in association with features for disclosing facts in regard to the patient and as to the gases.

Referring to the drawings:

Fig. 1 is a side elevation with parts broken away of an embodiment of the invention in a machine for cutting down high pressure gas supply and conducting such to a patient;

Fig. 2 is a detail view on an enlarged scale in plan of the relief valve at the mask;

Fig. 3 is a plan view of the apparatus of Fig. 1, parts being broken away;

Fig. 4 is a section on the line IV—IV, Fig. 2;

Fig. 5 is a front view of the apparatus of Fig. 1 from the left, with the delivery duct and vaporizer removed;

Fig. 6 is a section on the line VI—VI, Fig. 3;

Fig. 7 is a section on the line VII—VII, Fig. 3;

Fig. 8 is an end view from the right of the section of Fig. 7, parts being broken away and the cover plate being removed;

Fig. 9 is a section on the line IX—IX, Fig. 6;

Fig. 10 is a section on the line X—X, Fig. 3;

Fig. 11 is a partial section on the line XI—XI, Fig. 10;

Fig. 12 is a detail view from the inner side of the nitrous oxid chamber, with parts broken away;

Fig. 13 is a section on the line XIII—XIII, Fig. 12;

Fig. 14 is a section on the line XIV—XIV, Fig. 3; and

Fig. 15 is a section on the line XV—XV, Fig. 10.

Casters 4 are shown as mounting spider 2 carrying column 3 having bracket 4.

Nitrous oxid-oxygen

High compression gas supply tanks 5, 6, may be clamped by bolts 7 in heads 8 having valves 9 operated so that through coupling 10 the high pressure gas may be stepped down by reducing valve or regulator 11 as adjusted by screw or bolt 12 and held by clamp bolt 13 in arm 14 of the bracket 4 (Figs. 1, 5).

The column 3, extending above the bracket 4, mounts head 15 having arms 16, 17. The arm 16 has duct 17 thereto from the regulator 11 as in communication with one of the nitrous oxid tanks 6 extending to fitting 18 (Figs. 3, 5). The regulators 11, shown as provided with a pair of couplings 19, permit simultaneous assembly of

two tanks therewith so that as one tank is depleted the other tank may be cut in and the supply through the duct 17 not interrupted. The exhausted tank may be replaced and this accordingly provides operation facilities for the region over an extended interval even with small tanks.

The fitting 18, for the guidance of the operator, is shown as having notation 19 thereon. In the instance herein shown this is nitrous oxid as the anaesthetizing gas. This fitting 18 is in communication with passage 20 (Fig. 10) in the arm 16. From this passage 20 extends duct 21 to gage 22 (Figs. 3, 5, 12) for disclosing the pressure of the gas delivery as cut down by the nitrous oxid regulator 11 which may be say to fifty or sixty pounds, while the pressure at the tank may have originally been a number of atmospheres, say 3000# per square inch. In lieu of the auxiliary, or duplication of the tanks at the valve or regulator 11, one of the couplings 10 may be connected to a high pressure gage 22' (Fig. 3) so that the amount in the supply tank may be checked, and when so checked as the supply becomes reduced, the auxiliary new tank supply attached, before the depression gets down below that at which it is desired to keep the pressure as indicated by the gage 22.

The passage 20 has branch 23 having terminal port 24 in proximity to flexible rubber diaphragm 25 (Figs. 12, 13) providing chamber 26 having outlet passage 27 therefrom to depending tube 28 spilling into distensible chamber 29 of disk form about the tube 28. This chamber 29 is thus provided with a pair of parallel distensible diaphragms 30, 31. Housing plate 32 is protection and distension limit means for the diaphragm 31, while opposing plate or housing section 33 is for the distensible diaphragm 30 of the chamber 29.

Delivery pressure adjustment

The diaphragm 30 is shown as having insert metal plate 34 as a bearing for nose 35 of bent lever 36 (Figs. 5, 13) protruding through opening 37 in the housing section 33. The lever 36 has fulcrum bearing 38 in the arm 16 with short arm 39 upward therefrom engaging reduced end 40 of plunger 41 directed by guide 42 against the diaphragm 25 as a holding means for causing the lever 36 on distension of the chamber 29 to cut off gas supply to the chamber 29 by way of the port 24.

From the reserve or pressure supply tank 5 as connected (Figs. 1, 3, 5) through its reducing valve 11, supply of oxygen by way of duct 42' is

to fitting 18 having oxygen designation 43 as a convenience for the machine operator identifying the communication between the supply and the machine. This oxygen supply is effective through duct 20 in the arm 17 and discloses the oxygen pressure as passing the reducing valve at gage 44. The control of oxygen gas delivery at the reduced pressure to the oxygen chamber below the oxygen gage is analogous to that to the nitrous oxid chamber below the gage 22.

From the levers 36, as oppositely directed toward opposing diaphragms 38 is intermediate pair of links 45 having pivot pin connection 46 (Figs. 3, 5, 6). These links 45 thus provide a toggle from which there extends a yieldable resistance herein shown as comprising sleeve 47 having closure plug 48 as an abutment for compression helical spring 49 in the cylinder 41.

This spring 49 is oppositely held by pin 50 through stem 51 emerging past the plug 48 with clearance 52 for lateral play. This stem 51 extends through forwardly projecting arm 53 of the head 15. This arm 53 for this stem 51 has clearance way 54. The upper portion of this stem 51 has threaded portion 55 with which engages pinion nut 56 in mesh with pinion 57 on stem 58 fixed with knurled indicating disk 59 as disposed adjacent pointer 60 (Figs. 3, 6) on housing having hold-down portion 61 precluding axial shifting of the pinion 56. The knurled indicating disk 59 is shown as having notations 62. Accordingly, in rotating this disk 59 say for lifting the pin 51 by the operation of the nut 56 thereon, compression of the spring 49 is increased and there is accordingly a tendency to pull up the toggle pin 46 and resultantly increase the resistance to contraction which the levers 36 might have.

There is thus a building up of the operating pressure in the chambers 29 as effective for gas supply, which is of a pre-determined indication disclosed at the notation 62 and this notation is to the extent of fully cutting off the supplies of the gases herein disclosed as nitrous oxid and oxygen in coming to the automatic delivery valves at the predetermined reduced pressure which may be the millimeters of mercury above atmosphere below the range which is that for rupturing the lungs, say up to forty millimeters of mercury.

Proportioning

From the chamber 29 and about the passage 20 is discharge port 63 (Fig. 13) to passage 64 (Figs. 10, 15) in the arm 16. This passage 64 extends to port 65 centrally of the head 15. Here is central seat 66 for hollow plug valve 67 having port 68 movable to variable register with port 65 thus providing communication with chamber 69 on one side of partition 70 in the plug valve. This plug valve is provided with ledge 71 flush with the top of the partition 70 providing a seat for check disk 72 by gravity normally providing a closure for the chamber 69.

This plug valve above the disk 72 has chamber 73 in which is mounted bushing 74 carrying transparency 75 held therein by gasket 76 and sleeve 77 depending into the chamber 73 as a limit stop for the rise of the check disk 72.

The oxygen delivery from the oxygen chamber 29 is to passage 78 in the arm 17 (Figs. 10, 15) with flow to port 79 oppositely from the port 65 as to partition 70 of the plug valve 67. This plug valve 67 has therein stepped or tapered port 80 narrower at the lower proportions and widen-

ing up for greater width of port opening as the proportion increases for oxygen flowing through the ports 79 and ports 80 as brought into register in chamber 81 below the check disk 72 of the one-way gas flow valve.

From this chamber 73 are lateral ports 82 (Figs. 6, 11) to delivery passage 83 in the arm 53 of the head 15 for conducting the flow of gas from the two pressure sources of supply at the reduced pressure as separately coming to the valve 61 and together passing from up about the periphery of the valve 72 into the chamber 73.

The proportioning of these two different gases is effected by rotation of the plug valve 67 in its seat 66 in the head 15. This plug valve as protruding above the head 15 adjacent the bushing 74 has overhanging flange 84 (Figs. 1, 3, 6, 10) carrying scale 85 indicating percentage of oxygen as in position relatively to the pointer 60. The arm 53 has stop pin 86 with which pin 87 at the flange 84 coacts at the zero position of oxygen or 100% nitrous oxid, while the pin 88 coacts with pin 89 on the flange 84 as a stop at the 100% position of oxygen or zero nitrous oxid. As heretofore indicated, the zero oxygen and zero nitrous oxid is obtained by adjusting the dial 62 to off position at the pointer 60.

Micrometer operation or more delicate adjustment of the knurled flange 84 may occur in this proportioning, in lieu of handling this disk 30 direct, by operating disk 89 having scale 90 thereon. This disk 89 is loose on pin 91 fast in arm 92 from the head 15. Fixed with this disk 89 is pinion 93 in mesh with gear segment 94 carried with the flange 84 of the plug valve. This pin 91 additionally carries pointer 95 in proximity to the scale 90. It follows that by rotating the knurled disk 89 for disclosing graduations for oxygen per cent intermediate the readings on the scale 85 as disclosed by the 40 pointer 95 there is proportional rotation of the plug valve 67 and nicely of proportioning to a minor percentage may be determined and this gas is accordingly, as definitely proportioned, free to pass from the chamber 73 (Fig. 10) by 45 way of the passage 83 (Figs. 6, 11). Fitting 96 may provide the mounting connection for flexible duct 97, terminating in fitting 98 (Fig. 1) having rigid mask section 99 carrying flexible mask rim 100, as a delivery nozzle to the patient 50 by placing such over a respiratory orifice, as the nose or nose and mouth, in order that upon inhalation there may be such drop in pressure that the check disk 72, as gravity seating, will be poised for supply of the nitrous oxid and oxygen gases in the predetermined proportion to the patient. Upon exhalation the check valve 72 seats and the gas supply is cut off.

Relief

In the mask fitting 98 (Figs. 1, 2, 4) is branch bushing 101 terminating in seat 102 against which rests check disk 103 as held by compression helical spring 104. Threaded with the bushing 101 is extension sleeve 105 providing seat 65 for open-work disk or spider 106 having central guide 107 for plunger 108. The plunger 108 is provided with collar 109. Between this collar 109 and the spider 106 adjacent the guide opening 107 is compression helical spring 110 thereby 70 normally thrusting the plunger 108 upward to have the collar 109 against hood 111 of shell 112 having outlet ports 113.

In operation, manual depression of the plunger 108, at protruding push button portion 114 there-

of, materially increases the resistance of the spring 104 and accordingly in practice is a normal closure for the check disk 103 against spilling of exhalation by the patient. In normal 5 operation, the spill may be adjusted as to back pressure by rotating the shell 112 which is provided with inwardly extending or thread means 115 coacting with helical external groove 116 on the extension sleeve 105 fixed by pin 105' 10 with the fitting 98. By the rotation of the shell 112 relatively to the sleeve 105 the clearance 15 between the collar 109 and the spider 106 is reduced and there is increased compression of the spring 104. Calibration marker or pointer 117 is provided on the housing 98 with scale 118 on the shell 112 say in steps of five millimeters of mercury up to twenty, or other pressure as desired, thereby determining the exhalation pressure 20 at which the valve 103 may be unseated for spill of exhalation from the patient.

Rebreathing

With such exhalation from the patient, some 25 of the supplied gases do not get into the lungs for taking up by the system of the patient and are exhaled uncontaminated. Other portion of the exhalation includes the gases given up by the patient, say carbon dioxide as well as inert gases rejected. Importance attaches not only 30 to conserving the supplied gases for anaesthesia and oxygen for maintaining life activities, but there is purpose in the carbon dioxide as an excitant to respiratory action. Herein measure is taken to effect return of exhalation gas in advance of any re-supply of nitrous oxide, oxygen, 35 or other gases, thereby insuring that the carbon dioxide of the previous exhalation may get to the patient for promoting a degree of lung action desired.

40 To this end the duct 83 is in direct communication through the ports 82 and chamber 73 with passage 119 (Fig. 6) in the arm 92. This passage 119 extends to gusseted chamber 120 as a rebreathing bag or reservoir in shield or 45 housing having section 121 toward the column 3 and fixed with the head 15 and additional section 122 on pivot bearing 123 adjacent the mounting of the flexible or distensible chamber 120 with the arm 92.

50 From this it follows that a gas flow from exhalation, cut off by check valve 72 from getting therebelow in the plug valve, flows through the passage 119 to inflate this chamber 120 and thus swing the arm 122, as depending, outward on its 55 fulcrum 123. This chamber 120 is accordingly collapsible and distensible over a range. This range in practice as adopted herein may be 1200 cc. or a range beyond the tidal volume usually experienced with patients. This chamber is thus 60 responsive for filling, and upon inhalation, is responsive for emptying.

Hereunder, as an important feature of handling the patient, there may be attained effective emptying of the chamber 120 before the 65 check valve 72 lifts for further supply of gases to the patient. This advance expulsion or emptying of the chamber 120 is effected by loading mechanism herein shown as involving cam 124 on the shield section 122. Roller 125 on depending 70 arm 126 rides on this cam 124 to approximate uniform pressure as the shield 122 swings outward during the inflation of the chamber 120. This arm 126 is engaged by end 127 (Figs. 6, 9) of torsion spring 128 about shaft 129 which has 75 fixed terminal connection 130 with collar 131

fast on this shaft 129. This shaft 129 is under hood or housing 132 and terminally protrudes in shield 133 (Fig. 3) to house worm wheel 134 (Figs. 8, 9). Worm 135 is in mesh with this worm wheel 134 and may be operated by key 136. The angle of friction is sufficient to hold the worm 135 in the adjusted position, while the 10 operation of the key 136 is effective for increasing or decreasing the torsion action of the spring 128.

This means that this rebreathing chamber 120 may be adjusted to open at a pressure which in practice is desirably just below and effective in advance of unseating valve disk 103 at the mask. The shield 133 (Fig. 3) is provided with 15 pointer 137 fixed therewith in the vicinity of window 138. Fixed with the worm wheel 134 is scale 139 movable in the operation of the key 136 past the window 138 for disclosure by the pointer 137 as the resistance, say in millimeters 20 of mercury, against inflation of the chamber 120, which may thus be visibly checked with the adjustment at the relief valve.

Rebreathing volume adjustment

25 Loosely mounted on the shaft 129 is arm 140 (Figs. 1, 7, 8, 9) having offset 141 projecting into the range of opening movement of the housing section 122 and thereby affording a stop. This arm 140 is provided with pin 142 carrying 30 pawl 143 normally thrust by torsion spring 144 into engagement with fixed ratchet 145 carried by end portion 146 of the housing 132. The pawl 143 is held in the plane of the ratchet 145 by side cheeks 147. Handle 148 may be grasped and 35 swung clear of the ratchet 145 for the attendant to locate the stop 141 in desired positions for maximum inflation of the chamber 120.

Rebreathing volume disclosure

40 The housing 132 above the shaft 129 carries bracket 149 (Figs. 7, 9) mounting shaft 150. Loosely mounted on this shaft 150 is arm 151 carrying scale 152 disclosed through window 153 (Fig. 3) of the housing 132. Additionally, also 45 loosely mounted on the shaft 150, is pointer 154 protruding through the window 153 to disclose a reading on the scale 152. Compression helical spring 155 between these loose arms 151 and 50 154 and about the shaft 150 interposes a frictional resistance for retaining location of this scale 152 as adjusted by handle 156 and for the pointer 154 disposed to be engaged by supplemental pointer 157.

55 The supplemental pointer 157 is also loosely mounted on the shaft 150 as an angle lever and carries short arm 158 (Fig. 7) connected by link 159 to bracket 160 mounted on the depending swinging shield section 122 about the chamber 120 movable in response to inflation of such chamber. It thus follows that this inflation movement of the chamber 120 is transmitted to shift the pointer 157 along the scale 152 to pick up the pointer 154 at the maximum range of shifting 60 during the inflation, and as the chamber 120 is 65 emptied or deflated the pointer 157 recovers leaving the pointer 154 to show on the scale 152 the volume in 100 cc., an instance herein disclosing rebreathing permitted say at the adjustment of the stop 140.

70 For checking full tidal volume of the patient, the head 114 may be depressed to hold the relief valve from opening and the pawl 143 clear of the ratchet 145. Preferably this may occur with a minimum of pressure as applied by the key 136, 75

5 although it may be at the operating pressure as determined for the patient. At this exhalation, the pointer 157 is effective say in shifting from zero on the scale 152 up to the range of the exhalation volume. This carries the pointer 154 so that it is not encumbent upon the operator to watch for the pointer 157, for the pointer 154 will rest at this tidal volume limit.

In the operations hereunder, the adjustment of the scale 152 by the handle 156 permits the location of the zero point on this scale at the deflation or emptying position of the chamber 120 as the minimum before re-inflation.

15 *Emergency oxygen*

In the arm 17 the duct 20, to which the oxygen from the flexible duct 42' is supplied through fitting 18, is shown as having provision for bypassing the proportioning valve and check disk. Branch 161 (Fig. 10) from the duct 20 has therein bushing 162. Opposing this bushing 162 is additional bushing 163 providing guide for plunger 164 terminating in head 165 against the lower side of flexible rubber diaphragm 166.

25 side of flexible rubber diaphragm 101.
Threaded on this bushing 163 is cap 167 holding
the diaphragm 166 in position, this cap having
a central opening 168 therethrough. Push
button 169 protrudes through this opening 168
and has within the cap 167 enlargement 170
bearing on the diaphragm 166 oppositely to the
head 165. Depression of this push button 169
is effective through stem 171 to thrust fiber seat
172 away from closure position at the port at
the lower end of the bushing 161. This thrust-
ing of the push button 169 as transmitted to this
seat 172 in collar 173 is resisted by compression
spring 174 normally holding this port closed. It
follows from this depression of the push button
169, unseating of the valve 172 allows the high
pressure oxygen from the passage 20 to flow past
the bushing 161 about the stem 171 into passage
175 to discharge by port 176 through ports 82
(Figs. 10, 11) in the plug valve for this high pres-
sure oxygen supply, not only to pass above the
40 disk 12, but flow directly through the passage 83
as a lung inflating spurt to the patient directly
responsive to the pressure of the push button,
with cut off at once the pressure is released at
45 such push button 169.

Carbon dioxid

In lieu of rebreathing or as a definite supplemental supply for anaesthesia or excitant, carbon dioxide as an additional minor gas volume may be supplied say from pressure cylinder 171 past reducing valve or regulator 178 to flow through duct 179 to fitting 180 (Figs. 1, 3, 10), provided with seepage port 181 at phenol condensation product seat and tapered valve 182 having scale notation 183 movable as to pointer 184. This scale as disclosed, say with the carbon dioxide pressure at sixty pounds will give the direct reading of say 100 cc., 300 cc., and 500 cc. per minute spill past this seepage port 181, to flow from this fitting 180 by branch duct 185 by-passing the oxygen emergency for direct flow into the passage 175 and thus for intermingling with the delivered or exhalation gases independently of supply of new gases. This means minimizing of any carbon dioxide dilution of new gases and involves a maintenance of the accuracy for this minor volume supply as continuous and collateral which is spilled to the patient direct at the adjusted rate.

Supplemental anaesthesia gas

In parallel with or in lieu of nitrous oxid, ethylene may be used, and to this end adjacent the fitting 18 bearing the notation 19, there is provided fitting 18 bearing ethylene notation 186 as a supply to the passage 20 in parallel with or in lieu of the nitrous oxid supply from the duct 11. The ethylene supply to the fitting 18 may be from pressure tank source through reducing valve or regulator and thence by flexible duct 187. 10

Vaporizer

Additional supplemental anaesthesia promotion may be from a vaporizer liquid source as ether. For such, there is shown herein introduced in the duct 83 by coupling 188 head 189 (Figs. 1, 3, 14) of vaporizer. This head 189 is provided with ether cup or chamber 190 which may have charge 191 of ether therein. The head 189 is provided with flange 192 carrying a pair of depending concentric foraminous cylinders 193, 194, as a housing for fiber 195 serving as a capillary attraction means for increasing the vaporizing surface of ether 191. The cylinder 193 is spaced inward from the outer portion of the cup 190 and the inner cylinder 194 leaves clearance for central chamber 196.

The head 189 is provided with scale 197 adjacent slot 198 through which protrudes handle 199. This handle as operating along this scale determines the ratio of gas flow to be by-passed from the direct flow between the passages 83 and 97 into this ether cup. This is effected by sleeve 200 to which the handle 199 is directly connected and through which sleeve this handle extends to anchor partition 201. This sleeve as rockable in the head 189 has port 202 on the supply side for registering with port 203 of the head 189 in communication above the flange 192 for flow of gas to pass into the cup 190 through the outer foraminous cylinder 193 over the ether impregnated fibrous material 195 thence out through the foraminous cylinder 194 into cylinder 196. As thus charged with ether vapor it flows upward through duct 204 and port 205 into head 189 through port 206 in the sleeve 200 on the opposite side of the partition 201 from the port 202, as an ether pregnant charging portion of the anaesthetizing gas.

This head 189 at the off position has the port 202 clear the port 203 and in register with port 207 in the head 189 (Fig. 3) for by-passing the ether cup by way of passage 208 and port 209 in register with the sleeve port 206 of the sleeve 200. It accordingly follows from the intermediate positions as indicated by the handle 199 on the scale 197, the ports 202 and 206 of the sleeve 200 are in partial register for splitting the gas flow between the ports 203 and 207 for entering and between the ports 206 and 209 as passing on to the patient. 50 55 60

In operation, the patient to be subjected to the anaesthesia has the mask 100 applied after a supply tank for each of the gases to be used is opened up and tested out through the machine, with all foreign gases thus removed and the mask has been subjected to inhalations and exhalations to operate the various valves for delivery and exhaust or relief. The mask 100 is then applied to the patient.

In practice it is usual to allow initially a few heavy or high percentage inhalations of the anaesthetizing gas, say the nitrous oxid. Then the machine is adjusted say by manipulating the 75

disk 87 to that percentage which seems to be adequate to hold the patient in the desired condition of anaesthesia or analgesia. At each inhalation the check disk 72 is lifted after the re-breathing bag 120 has collapsed. On exhalation, the check disk 72 first is seated, the bag 120 is then distended to the desired quantity for re-breathing, and thereafter the relief valve disk 103 at the machine opens for exhaust.

10 The operation of the re-breathing bag in advance of the new gas supply has a tendency to keep the respiration excitant carbon dioxide in such volume in the circuit as to promote the respiration cycle. With the purpose of increasing 15 progressively the accumulation of the carbon dioxide, the moments when respiration becomes to be progressively decreasing in volume, the carbon dioxide valve disk 183 may be operated for delivery directly into the machine in advance of 20 the new gas supply and continuously at desired flow rate.

This carbon dioxide affords a stimulation means for keeping the respiration normal as to rate and of an efficient depth in the lungs. As there is desired recovery, this supplemental gas supply of carbon dioxide may be cut out. Otherwise 5 hereunder as the mask is removed from the patient there is not fresh gas delivery, only as there may be building up of pressure through the manipulation of the disk 59.

What is claimed and it is desired to secure by 10 Letters Patent is:

A gas administering machine comprising an intermittently distensible re-breathing chamber providing a responsible replenishment device for the chamber, and means for adjustably establishing resistance to filling said chamber by said device embodying a plate member, pivotal mounting means for the member and adjustable loading means for the member rockable to and fro by the action of said member. 15 20

ELMER I. MCKESSON.

CERTIFICATE OF CORRECTION.

Patent No. 2,042,474.

June 2, 1936.

ELMER I. McKESSON.

It is hereby certified that error appears in the printed specification of the above numbered patent requiring correction as follows: Page 5, second column, line 14, in the claim, for the word "responsible" read responsive; and that the said Letters Patent should be read with this correction therein that the same may conform to the record of the case in the Patent Office.

Signed and sealed this 18th day of August, A. D. 1936.

Henry Van Arsdale

(Seal)

Acting Commissioner of Patents.
